UNITED STATES PATENT OFFICE.

JOHN WALLACE PAGE, OF ADRIAN, MICHIGAN.

MOBILE ARMORED SHIELD.

1,189,474.

Specification of Letters Patent.

Patented July 4, 1916.

Application filed January 14, 1915. Serial No. 2,202.

To all whom it may concern:

Be it known that I, JOHN WALLACE PAGE, a citizen of the United States, residing at Adrian, in the county of Lenawee, State of Michigan, have invented certain new and useful Improvements in Mobile Armored Shields; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to armored shields especially adapted for use by infantrymen as a means of affording protection against the gun fire of an opposing force, and it consists in the novel features of construction 20 as hereinafter set forth and claimed.

The marked improvement in the construction and operation of modern fire arms, together with the introduction of newly developed high explosives, has so increased 25 the efficiency of men in warfare as to enable a comparatively small force defending a position to sweep the battlefield with such 30 volume and accuracy of fire from magazine-rifles and machine-guns as to render an open offensive or frontal attack, even though of 35 superior numerical force, extremely hazardous to attempt, and usually only successful at the expense of great sacrifice in loss of life. While material changes in the 40 strategy and tactics employed in military operations and the adoption of various means and methods in an effort to protect and safeguard the advance of an offensive movement have contributed in a measure to 45 lessen the hazard of the task, still the more favorable position and effective cover retains to the defenders the balance of advantage, and it is to overcome or at least neutralize this advantage that raises the primary object of the present invention.

To this end my invention contemplates the provision of comparatively simple and effi-

cient mobile means for affording protection to a body of infantrymen in moving action, against the gun fire of an enemy, whether in 50 an offensive or defensive engagement, so as to render such fire ineffective and enable a successful advance or retreat to be accomplished with a minimum loss in casualties 55 resulting from such action.

A further object of the invention is the embodiment in an armored shield of such a construction as will offer effective resistance to the penetration of projectiles in a manner to cause the destruction of the projectile and retard and retain the bursting particles against deflection to prevent injury therefrom, and which, while embracing these advantageous features will be comparatively light and readily mobile to enable it 60 to be conveniently transported and quickly moved about at will by a detachment of soldiers, as may be required to protect an advance upon an enemy's field-works or entrenchments, to shield a body of men in the 65 construction or destruction of entanglements or entrenchments, to serve as breastworks in field engagements and as a rearguard cover in executing a retreat.

The preferred form of structure embodying the essential feature by which the above objects are attained is illustrated in the accompanying drawings, in which:

Figure 1 is a plan view of the device constructed in accordance with my invention, as 80 it would appear in position for operation. Fig. 2 is an end elevation of the device and indicating by dotted lines the figures of soldiers thereon in position for action. Fig. 3 is a vertical longitudinal sectional view 85 taken on dotted line 3—3 of Fig. 2. Fig. 4 is a vertical transverse sectional view taken on dotted line 4—4 of Fig. 1. Fig. 5 is an enlarged fragmentary sectional detail view, showing the relative arrangement of the 90 layers forming the fabricated armor wall. Fig. 6 is a sectional detail of a portion of the fabricated armor wall as formed from a continuous length of fabric wound helically.

Referring to the drawings and to the characters of reference marked thereon, 1 designates a hollow drum or cylinder which may be of any desired diameter and length, and is preferably formed from sheet steel of a gage sufficiently light, consistent with the necessary strength, to sustain the contour of the cylinder, which may be further reinforced and strengthened by means of annular ribs 2 formed of angle iron and riveted, or otherwise secured, at intervals to the inner perimeter of the cylinder. The ends of the cylinder may also be provided with annular angle iron ribs 3 riveted thereto as at 4 so as to position one of the sides of the angles radially of the cylinder in the manner of a vertical flange to which a circular plate or head 5 may be secured by bolts or rivets as at 6 to form a closure for each end of said cylinder, as shown in Fig. 3.

The cylinder thus formed is adapted to serve as a drum or spool for the support of an outer or surrounding fabricated flexible armor wall 7, and as a means of mounting this armor wall so as to yieldably support it free from contact with the wall of the cylinder, and to distribute the supporting means so as to engage the fabricated wall at intervals and sustain it in a uniform arc concentric with said cylinder, a plurality of strips of angle iron 8 are riveted each through one of its flange portions to the periphery of the cylinder so as to extend circumferentially and horizontally thereof and dispose its other flange portion in the form of a radially projecting spiral rib, as shown in Fig. 3. Upon these ribs the fabricated armor wall 7 is formed and supported, being composed of a plurality of layers of interwoven metal strands 9, preferably of wire, which may consist of a series of superimposed single layers, or a continuous length of the fabric may be helically wound about the cylinder to form the wall of the desired thickness, as indicated in Fig. 6. The fabric being of uniform mesh and extending over increasing radii from the inner to the outer periphery of the wall formed thereby, will cause the transverse strands in the successive layers to overlap and effect a consequent reduction in the mesh of the fabricated wall, with the result that the interstices of the several layers will be so subdivided as to restrict the openings in the outer layers and obstruct the alining openings of the innermost layers against direct passage therethrough. By this construction a reticulated resilient wall is formed, having varying degrees of resistance to penetration, which will readily yield to cushion the force of impact of a fired projectile directed against it, and which, while not offering sufficient direct resistance to prevent penetration, will in receiving such projectile cause it to successively impinge upon the intervening ob-

structing strands of the several layers in a manner to intermittently retard and alternately deflect the course of said projectile with the resultant effect of so altering the shape of the projectile as to destroy its equilibrium and impart an eccentric action to its rotary motion. This, while contributing to dissipate the energy of the projectile, will in conjunction with the force of the percussion resulting from the intermittent impacts set up such a succession of rapid and violent counterstresses as to cause the disintegration of the projectile within the fabricated wall, where the broken particles will be entrapped within the meshes 80 of the fabric.

In demonstrating the efficiency of an armor shield of the above described construction, thorough experimental tests have been made with the regulation military infantry rifle from which bullets were fired at various distances into the fabricated wire wall forming the target, with the successful result that, while in some instances the outermost strands of the wall were severed, the 90 bullets were invariably completely shattered or literally exploded upon penetrating the wall, and the torn fragments remained embedded in the meshes of the fabric.

It is therefore apparent that the present 95 invention is of the greatest importance as a defensive armament, not only because of its efficiency in resisting gun fire, but, because of its cylindrical formation, its utility is greatly enhanced through its mobility, 100 whereby it may be readily placed or quickly shifted by rolling it upon the ground as may be desired in maneuvering to gain an advantageous position, as well as affording an extensive circumferential area, any portion 105 of which is available for effective use at intervals by rolling the drum so as to present an unused surface when the exposed surface has become worn or damaged.

To provide means for conveniently handling the drum to enable it to be readily moved about by a body of men, while at the same time affording protection and serving as breastwork over which to fire upon an enemy, I have shown a limber or traction 110 frame 10, which may consist of two side rails 11, preferably of angle iron, pivotally connected at their forward ends respectively, and centrally to the ends of the cylinder 1 by means of a tubular shaft 12. This shaft 115 is supported by journal bearings 13 in the heads 5 of the cylinder, and extending through the ends of the side rails 11 is locked therewith by chained keys 14 which pass through said side rails and through the 120 ends of said shaft. (See Fig. 3.) The rear ends of said side rails are connected by a tubular shaft 15 which is secured at its ends by chained keys 14', and journaled upon the shaft at opposite ends within the 125 130

side rails are trailer wheels 16 held in position thereon by collars 17 and adapted to bear upon the ground to carry the trailing end of the frame or limber.

5 One or more rods or tubes 18 may be secured at their ends within the side rails by chained keys 14², and extended across within the frame to serve as handles to be grasped by a body of men in running the shield 10 about, as indicated by the dotted figure in Fig. 2, in which operation it will be understood the drum will roll upon its periphery carrying the forward end of the frame upon the shaft 12, and the rear end upon the 15 trailer wheels 16, or the rear end of the frame or limber may be lifted bodily where a sufficient number of men are available, to carry or swing it about in changing or directing the course of the drum.

20 A step or platform consisting of a channeled foot strip 19, having end uprights 20 attached thereto, may be suspended between the side rails of the frame by means of studs 21 extending through said uprights and 25 side rails, and receiving through their outer ends chained keys 14³, the height of the platform being such as to enable a rifleman standing thereon to fire over the drum, as shown by the figure indicated by dotted 30 lines in Fig. 2, when employing the shield in the manner of a breastwork.

It will be noted that as all of the connecting parts of the frame or limber are detachably locked by chained pins, which may be 35 readily inserted and withdrawn, that the assembling and disassembling of the device may be conveniently and quickly accomplished.

Having thus fully set forth my invention, 40 what I claim as new, and desire to secure by Letters Patent, is:

1. An armored shield comprising a wall composed of a plurality of layers of reticulated metallic fabric superimposed and relatively disposed to cause a variable reduction 45 in the mesh throughout the thickness of the wall, and thereby form a reticulated resilient wall yieldable to the force of impact of a projectile and offering increasing degrees 50 of resistance at intervals to retard and deflect it against direct penetration, and means for supporting said wall upon one side thereof.

2. An armored shield comprising a wall 55 composed of a plurality of layers of woven metal strands superimposed and relatively disposed to intercalate the strands and interstices of the successive layers so as to effect a corresponding reduction in the mesh of the 60 fabric with the increasing thickness of the wall, whereby a projectile impinging alternately upon the strands forming and intersecting the interstices of the layers is intermittently retarded and deflected in such 65 rapid succession of counter impacts as to

arrest and neutralize the force of its energy, and means for rigidly supporting said wall at intervals.

3. An armored shield comprising a cylindrical wall composed of a plurality of layers 70 of woven metal strands superimposed and relatively shifted to position the strands of the successive layers in overlapping relation and differentiate the mesh throughout the fabricated wall formed thereby, and a cylindrical support for said wall. 75

4. An armored shield comprising an annular wall composed of a plurality of helically wound layers of woven metal strands superimposed and relatively combined to 80 intercalate the strands of the successive layers and graduate the mesh throughout the body of the wall formed thereby, a cylindrical support for said wall, and bearing members interposed at intervals between 85 said support and wall upon one side thereof.

5. An armored shield comprising a cylinder having radially extending ribs at intervals of its periphery, an outer wall supported on said ribs concentric with said 90 cylinder and composed of a plurality of superimposed layers of reticulated metallic fabric relatively staggered to vary and restrict the mesh of the wall as compared to that of the successive layers, and form a 95 reticulated armor wall of a drum adapted to roll upon the ground and serve as a shield to arrest fired projectiles.

6. In a rolling armored shield, an inner cylinder closed at its ends and having a 100 plurality of radially extending ribs on its periphery, an outer armor wall supported on said ribs concentric with said cylinder and composed of a plurality of layers of woven wire fabric of varying mesh forming 105 the peripheral wall of a drum adapted to roll upon the ground, a limber frame pivoted to the ends of said cylinder and adapted to trail upon the ground, and having handle bars by which said frame and 110 drum may be manually moved.

7. In a rolling armored shield, an inner cylinder closed at its ends and having a 115 plurality of radially extending spiral ribs disposed at intervals on its periphery, an outer armor wall supported on said ribs and composed of a plurality of layers of woven wire fabric forming the peripheral wall of a drum adapted to roll upon the ground, a shaft journaled in the ends of said cylinder, a limber frame pivoted at its forward ends to the ends of said shaft and having wheels at its rear ends adapted to bear upon the ground, a handle bar connecting the sides of said frame, and a platform suspended upon said frame. 125

8. An armored shield composed of a continuous length of woven reticulated metal fabric helically wound in superimposed layers to form a reticulated resilient annular 130

armor wall of a drum adapted to roll upon the ground, in which the successive layers are relatively staggered to intercalate and restrict the meshes and obstruct the interstices of the wall against direct passage therethrough, whereby a projectile in penetrating the wall is deflected and retarded by successive impingement upon a plurality

of layers and the force of its energy is neutralized.

In testimony whereof I sign this specification in the presence of two witnesses.

JOHN WALLACE PAGE.
